US00D882552S

(12) **United States Design Patent** (10) **Patent No.:** **US D882,552 S**
(45) **Date of Patent:** **** Apr. 28, 2020**

(54) **YODE FOR LOUDSPEAKER**

(71) Applicant: **TYMPHANY ACOUSTIC TECHNOLOGY (HUIZHOU) CO., LTD.**, Huizhou, Guangdong Province (CN)

(72) Inventors: **ZhiWen Chen**, Huizhou (CN); **Hong Zai Xie**, Huizhou (CN)

(73) Assignee: **TYMPHANY ACOUSTIC TECHNOLOGY (HUIZHOU) CO., LTD.**, Huizhou, Guangdong Province (CN)

(**) Term: **15 Years**

(21) Appl. No.: **29/646,570**

(22) Filed: **May 4, 2018**

(30) **Foreign Application Priority Data**

Nov. 6, 2017 (CN) 2017 3 0540343

(51) **LOC (12) Cl.** **14-01**

(52) **U.S. Cl.**

USPC **D14/222**

(58) **Field of Classification Search**

(57) **CLAIM**

We claim, the ornamental design for a yoke for loudspeaker, as shown and described.

DESCRIPTION

FIG. 1 is a top perspective view of a yoke for loudspeaker, showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 4 Drawing Sheets
